Paul Pinchard, Attorneys

UNITED STATES PATENT OFFICE.

THOMAS J. KENNEDY, OF PITTSBURGH, PENNSYLVANIA.

DOOR SUSPENSION.

Application filed September 26, 1924. Serial No. 740,005.

To all whom it may concern:

Be it known that I, THOMAS J. KENNEDY, a citizen of the United States, residing at Pittsburgh, in the county of Allegheny and State of Pennsylvania, have invented certain new and useful Improvements in Door Suspensions, of which the following is a specification.

This invention relates to door constructions and more in particular to a method of suspending screen doors or other types of doors which are subject to periodical removal.

The primary object of this invention is to provide a device which permits the installation or removal of a door without in any way affecting the hinges thereof. Another object is to provide a means of suspension for such doors which can be readily applied to old constructions without requiring important alterations. A further object is to provide such a device which is simple in construction and application and which can be manufactured at low cost. Additional features and advantages of this invention will appear from the following description considered in connection with the accompanying drawing forming a part of this application, and in which:

Fig. 1 is a fragmentary front elevation of a screen door suspended in accordance with this invention.

Fig. 2 is a cross-section taken on line 2—2, Fig. 1.

Fig. 3 is a cross-section taken substantially on line 3—3 in Fig. 1.

Fig. 4 is a perspective view showing a "female" clamping member used in Fig. 1.

Fig. 5 is a similar view showing a "male" clamping member adapted to cooperate with the female clamping member.

Fig. 6 is an elevation of a spacer-block used in the construction shown in Fig. 1.

Fig. 7 is a fragmentary front elevation showing a modified way of suspending a screen door.

Fig. 8 is an enlarged detail sectional view showing the clamping means used in Fig. 7.

Fig. 9 is a front view of the "female" clamping element used in Figs. 7 and 8.

Fig. 10 is a perspective view of one type of spacing member adapted to the construction shown in Fig. 7.

Referring to Figs. 1 to 6, which represent

the preferred construction for use in connection with new screen door installations, the screen door 1 is supported by means of hinges 2 permanently secured in the stile 3 of said door and in a supporting-strip 4, of wood, fitting within the rabbeted portion 5 of the door-jamb 6 and extending in parallel relation to the stile from the top of the door-sill-plate 7 to within a short distance of the transom 8.

This supporting-strip is securely clamped to the rabbeted portion of the jamb by means of detachable clamping devices each formed of a "female" clamping-member 9 and a "male" clamping-member 10. The former are preferably screwed permanently in recesses 11 cut in the door-jamb, whereas the latter are permanently fastened to the supporting-strip 4 at the proper levels to permit the engagement of said members and 75 the bearing of the supporting-strip on top of the sill-plate.

The recesses 11 are cut sufficiently deep to fully accommodate the clamping members and cause the supporting-strip to be 80 clamped tight against the door-jamb, thereby preventing any loose play or rocking motion of the strip when swinging the screen door.

The supporting-strip is clamped in position by first raising it high enough to enable the male clamping members to engage their corresponding female members from the top; this strip is then forced down to obtain a good engagement between the wedge-shaped contacting surfaces 12 and 13 provided respectively in the female and male clamping members, until the lower end of the supporting-strip bears upon the sill-plate. As will be seen in Fig. 1, the recesses 95 11 are made sufficiently long to allow the insertion of the male clamping members from the top of the female members.

The space 14 left between the top of the supporting-strip and the transom is now 100 filled up by means of a suitable spacer-block 15 to prevent the supporting-strip from working loose and to keep the clamping members always in proper engagement.

As illustrated in Figs. 1 and 6, this 105 spacer-block is shown as being provided with two nails 16, the protruding ends of which are intended to be driven into the door-jamb. As will be understood, other means for removably fastening the spacer- 110

block could be used, such as screws, hinges, etc.; but all these means are too well known to the art to require further comment.

The modified construction shown in Figs. 5 to 10 is intended especially for use in connection with old screen door installations, where it is not found desirable to reduce the width of the doors to provide sufficient room for inserting the wooden supporting-strips, 10 as used in Fig. 1.

In practice, most screen doors fit rather loosely within their rabbeted frames, and the object of this modification is to provide supporting-means which may be installed 15 directly within the clearance usually found between the screen doors and the jambs.

Referring to the drawing, it will be seen that the screen-door 17 is hung by means of hinges 18 to a supporting-strip 19 made of 20 angle iron of such thinness as to allow the insertion of one side thereof within the clearance space 20 existing between the stile 21 and the rabbeted jamb 22. The supporting-strip is held tightly against the 25 jamb by means of a suitable number of inwardly directed tongues 23, preferably made integral with the supporting-strip by the process of stamping. They engage 30 apertures 24 provided in the holding-plates 35 which are set in the door-jamb and permanently secured thereon by means of screws 26. These tongues are suitably bent to facilitate their insertion in the plates and to clamp the strip tight against the 40 jamb when in their final position. A suitable recess 27 is cut in the jamb back of each 45 aperture in the plates to provide room for the tongue. The spacer-block used at the top of the angle iron supporting-strip is 50 preferably made of metal and comprises a flat piece 28 in which two sharpened pins 29 are secured, to be driven in the jamb by 55 means of a hammer.

Referring to the above, the method of 55 applying doors built in accordance with this invention will be readily understood and may be succinctly stated as follows. Assuming that one desires to remove a screen door, he first opens the door and then removes 60 the spacer-block (which is not held very strongly in place by its short nails), after which the door, with its supporting-strip is removed by lifting it until the clamping members are disengaged. The screen doors are then stored away until needed again. 65 The method of hanging the doors is, of course, the reverse of that for removing them and will be understood without additional description.

60 It is thus seen that with this construction, screen doors may be applied or removed

very rapidly and without having to contend with the hinge-screws. Also, the trouble of having to re-set the hinges, owing to the wearing out of the screw-holes by frequent handling of the screws is eliminated. 65

As will be understood, as suggested herein, there may be slight changes made in the construction and arrangement of the details of this invention without departing 70 from the scope of the same, and I intend to include all such variations, as fall within the scope of the appended claims, in this application, in which the preferred forms only of my invention have been disclosed. 75

What I claim is:—

1. In combination with a door, a supporting strip positioned alongside of the jamb of said door and of lesser height than said jamb; a plurality of hinges for securing said door to said strip; clamping means for removably securing said strip to said door-jamb, and a spacer block adapted to prevent the lifting of said strip. 80

2. In combination with a door, a supporting strip positioned alongside of the jamb of said door and of lesser height than said jamb; a plurality of hinges for securing said door to said strip; clamping means for removably securing said strip to said door-jamb, said clamping means comprising a wedge shaped female member and a male member engaging the former, and a spacer block adapted to prevent the lifting of said male member out of said female member. 85 90 95

3. In combination with a door, a supporting-strip; a plurality of hinges for securing said door to said strip; clamping means to fasten said strip to a door-jamb, said clamping means comprising each a female member permanently secured to said door-jamb and a male member secured permanently to 100 said supporting strip, and a spacer-block adapted to prevent the lifting of said male 105 clamping members out of said female clamping members.

4. In combination with a door, a supporting-strip; a plurality of hinges for securing said door to said strip; clamping means to fasten said strip to a door-jamb, said clamping means comprising each a female member permanently secured to said door-jamb and a male member secured permanently to 110 said supporting-strip, and a removable 115 spacer-block adapted to prevent the lifting of said male clamping members out of said female clamping members.

In testimony whereof I affix my signature.

THOMAS J. KENNEDY.
